UNITED STATES PATENT OFFICE

125,125

DESIGN FOR A WALL BRACKET FOR ELECTRIC LIGHTING

John W. Brooks, Syracuse, N. Y., assignor to Pass
& Seymour, Inc., Solvay Station, Syracuse, N. Y.,
a corporation of New York

Application July 19, 1940, Serial No. 93,794

Term of patent 14 years

To all whom it may concern:

Be it known that I, John W. Brooks, a citizen of the United States and resident of Syracuse, county of Onondaga, and State of New York, have invented a new, original, and ornamental Design for a Wall Bracket for Electric Lighting, Design of which the following is a specification, reference being had to the accompanying drawing, forming a part thereof, and in which:

Figure 1 is a front elevation of a wall bracket for electric lighting showing my new design; Figure 2 is a side elevation thereof; and Figure 3 is a top plan view thereof.

I claim:

The ornamental design for a wall bracket for electric lighting, substantially as shown.

JOHN W. BROOKS.
